(57) **CLAIM**

I claim, the ornamental design for a jewelry, as shown and described.

DESCRIPTION

FIG. 1 is a front elevation view of a jewelry, showing my new design, the opposite rear side being a mirror image thereof; and,

FIG. 2 is an enlarged partial view thereof showing an end of the jewelry, the opposite side being a mirror image thereof.

1 Claim, 2 Drawing Sheets

FIG. 1

FIG. 2
